UNITED STATES PATENT OFFICE.

HANSON E. WADDELL, OF CHICAGO, ILLINOIS.

FLOWER-HOLDER.

No. 877,145.

Specification of Letters Patent.

Patented Jan. 21, 1908.

Application filed May 13, 1907. Serial No. 373,324.

To all whom it may concern:

Be it known that I, HANSON E. WADDELL, a citizen of the United States of America, and a resident of Chicago, in the county 5 of Cook and State of Illinois, have invented certain new and useful Improvements in Flower-Holders, of which the following is a specification.

This invention relates to cut flower holders, and has for its object to provide a simple 10 and efficient structural formation and combination of parts by means of which the cut flowers, with stems of any length, are held in bowls of glass or the like in a natural and efficient manner for table decoration and like 15 purposes; all as will hereinafter more fully appear.

In the accompanying drawings: Figure 1, is a perspective view of a flower holder embodying the present improvement. Fig. 2 is 20 a central vertical section of the same.

Similar numerals of reference indicate like parts in both views.

Referring to the drawings, 1 represents 25 the weighted supporting base of circular shape, formed of a heavy substance such as lead, and having a thickened marginal portion 2, a thin central imperforate stem supporting port web 3 having a reinforcing central 30 boss 3^a, and a chamber 1^a, as shown.

4 are stem stay disks or plates, preferably two in number, and formed with a number of closely arranged orifices 5 for receiving the stems of cut flowers and supporting the same 35 in the proper upright position upon the web 3 of the base.

While the scope of the present invention involves the use of a single plate or disk 4, in connection with a supporting base 1, and 40 held in adjacent and separated relation thereto, the preferred construction comprises a counterpart pair of such disks or plates, held in proper separated relation to each other and to the base 1 by a series of vertical connecting members or bars 6, as shown.

7 is a handled stem, the lower portion of which is screw-threaded and adapted to screw into a central screw-threaded orifice in the base 1, to afford a convenient means for 50 handling the holder. Such stem is capable of ready detachment when not required.

Having thus fully described my said invention what I claim as new and desire to secure by Letters Patent, is:—

1. A flower holder comprising a weighted 55 base formed with a thin central stem supporting web, a thin stem stay plate having orifices, and a series of vertical bars secured to the stem stay plate and to the weighted base to hold these parts in spaced relation. 60

2. A flower holder comprising a weighted base formed with a thin central imperforate stem supporting web, a thin stem stay plate having orifices, and a series of vertical bars secured to the stem stay plate and to the 65 weighted base to hold these parts in spaced relation.

3. A flower holder comprising a weighted base formed with a thin central stem supporting web, thin stem stay plates having 70 registering orifices, and a series of vertical bars secured to the stem stay plates and to the weighted base to hold these parts in spaced relation.

4. A flower holder comprising a weighted 75 base formed with a thin central stem supporting web, a thin stem stay plate having orifices; a series of vertical bars secured to the stem stay plate and to the weighted base to hold these parts in spaced relation, and 80 a handled rod extending through the stem stay plate and secured to the weighted base.

5. A flower holder comprising a weighted base formed with a thin central stem supporting web provided with a screw threaded 85 central orifice, a thin stem stay plate having orifices; a series of vertical bars secured to the stem stay plate and to the weighted base to hold these parts in spaced relation, and a handled rod extending through the stem stay 90 plate and having a screw threaded lower portion detachably secured to the screw threaded central orifice of the supporting web of the weighted base.

Signed at Chicago, Illinois this 11th day of 95 May 1907.

HANSON E. WADDELL.
